UNITED STATES PATENT OFFICE.

VAN QUINTON MURDOCK, OF COLUMBUS, OHIO.

PENCIL GRIP.

1,421,535.

Specification of Letters Patent.

Patented July 4, 1922.

Application filed June 13, 1921. Serial No. 477,240.

To all whom it may concern:

Be it known that I, VAN QUINTON MURDOCK, citizen of the United States, residing at Columbus, in the county of Franklin and

5 State of Ohio, have invented certain new and useful Improvements in Pencil Grips, of which the following is a specification.

This invention relates to a new and improved pencil grip.

10 The main object of the invention is to provide a new and improved pencil grip that is especially designed to be used in connection with pencils of metal or "Eversharp" type so as to prevent the pencil from slipping 15 from the hand of the operator during its manipulation.

A further object of the invention is to provide an improved grip that can be used in connection with pencils of conventional form 20 and whose use does not necessitate the changing of the construction or alteration of the pencil in any way.

Another object of the invention is to provide a grip of the above character that is 25 simple in construction, strong and durable and which it is believed may be manufactured at a low cost.

Various other objects and advantages will 30 become apparent during the continuance of the following description.

In the drawings:—

Figure 1 is a view in elevation showing my invention in its preferred embodiment and as applied to a pencil of the "Ever-sharp" type.

Figure 2 is a view in longitudinal section of my invention, showing the pencil partly broken away, and in elevation.

Figure 3 is a view in perspective of one 40 of the metal holders or bands used in connection with my invention.

Figure 4 is a view in perspective of the flexible body of the grip and the insert carried thereby.

45 Referring more particularly to the drawings wherein like numerals designate like parts throughout the several views, 10 and 11 designate the metal bands or holders used as a part of my invention. The bands or 50 holders are designed to fit snugly on the body of the pencil 12 and are only very slightly larger in diameter than the outer diameter of the body of the pencil.

The opposed faces of rings or carriers 10 and 11 are cut away to provide circular 55 sockets 13 which when the rings or carriers are positioned on the pencil, are open to the adjacent outer surface of the pencil as clearly shown in Figure 2.

An elongated sleeve 14 preferably formed 60 of leather or other flexible material is interposed between the rings or carriers 10 and 11 and its end portions fit the circular sockets 13 of the rings or carriers. However, the sockets are of greater width than the 65 width of the material forming the sleeve 14, as shown in Figure 2, so that the second sleeve or insert may be accommodated such as will be presently described.

In order to form a more compact structure 70 and at the same time prevent the sleeve 14 from becoming too loose with respect to the pencil and sliding too freely thereon, I provide a second sleeve or insert 15 that is formed of tape or other suitable and desirable material that fits snugly within the sleeve 14 and has its end portions resting within the sockets 13. The insert fits snugly about the outer surface of the pencil 12 and will prevent the grip from sliding too freely 80 thereon.

From the above it will be observed that the grip may be quickly and easily associated with the pencil and that by reason of the snug fit provided by the insert 15 and the 85 metal bands or carriers 10 and 11, it will be held snugly thereon and will not slide too freely. During the manipulation of the pencil, the operator's fingers grip the sleeve 14 so as to force the same more firmly into 90 engagement with the pencil and it has been found that the pencil can be more securely held and more easily manipulated.

From the foregoing it is believed that the other advantages and novel features of my 95 invention will be readily understood and therefore further detailed description is deemed unnecessary.

What is claimed is:—

1. In a device of the character described, 100 the combination with a pencil of spaced rings or carriers positioned on said pencil, said rings or carriers being provided on their opposed faces with sockets, a flexible sleeve interposed between said rings or carriers 105 and having its end portions fitting into said

sockets, and an insert carried by said sleeve between the same and said pencil, substantially as described.

2. In a device of the character described, 5 the combination with a carrying structure of spaced rings positioned thereon, said rings being provided with sockets on their opposed faces, a sleeve interposed between said rings

and having its end portions fitting said sockets, said sleeve being flexible, an insert 10 being interposed between said sleeve and said body portion, and the ends of said insert also being seated in said sockets substantially as described.

In testimony whereof I affix my signature.
VAN QUINTON MURDOCK.
